(57) **CLAIM**

The ornamental design for a toolholder, as shown and described.

DESCRIPTION

FIG. 1 is a right side perspective view of the toolholder showing our new design. The left side perspective is a mirror image of the right side perspective;

FIG. 2 is an enlargement of a portion of the toolholder illustrated in FIG. 1;

FIG. 3 is a top view of the toolholder illustrated in FIG. 1;

FIG. 4 is a bottom view thereof;

FIG. 5 is a side view of the toolholder along lines "5-5" in FIG. 3; and,

FIG. 6 is a side view of the toolholder along lines "6-6" in FIG. 3.

The phantom line showing, indicated by continuous equally spaced dashes, is environmental only and forms no part of the claimed design.

The broken line showing, indicated by alternating long and short dashes, is used for defining a boundary of the claimed part.
